RAILWAY CAR TRUCK

Harry A. Moeller, Bexley, Ohio, assignor to The
Buckeye Steel Castings Company, Columbus,
Ohio

Application October 21, 1933, Serial No. 694,667

7 Claims. (Cl. 105—207)

This invention relates to improvements in car trucks and more especially to novel wear plates for railway truck side frames and bolsters.

In railway car trucks it is customary to engage the truck side frames and bolsters in a more or less loose fitting manner so as to permit the truck bolster to movably cooperate with the frames and to maintain proper engagement between the frames and bolsters as the truck springs reciprocate under load and during transit. This produces relative motion between each truck bolster and the opposed side frames at the regions commonly known as the columns on the frames and the column guide surfaces on the bolster. This relative motion combined with transverse forces, as well as forces in the direction of the track, causes wear to take place between the engaging surface. In time, and especially in the case of trucks receiving such severe service as tender trucks, these wear surfaces become worn to the extent that renewal thereof is necessary.

Provision for renewing wear surfaces is not fundamentally new. However recently considerable effort has been made in the direction of welding on to the original castings renewable plates which, when worn, are simply renewed and replaced, thereby restoring the original dimensions. In one such proposal wear plates formed of pressed channel pieces of metal are welded to the bolster and to the frame. The mechanical difficulties encountered in an application of this character arise from the fact that in bending plates to channel form there is a certain amount of variation between different plates, even though they are bended by the same dies. This variation comes about by the wear on the dies and possibly heat treatment of the plates, and the variation in gauge of the plates themselves. This variation, therefore, makes it difficult to obtain a snug fit between the channel plates and the surfaces on the frames and bolsters to which these plates are attached. This condition of fitting could be improved somewhat by accurately machining the castings to fixed dimensions, in which case all the variations would reside in the plates. Machining of castings is an expensive operation.

The primary object of the present invention is to eliminate the above mentioned disadvantages and I have found it would be entirely satisfactory to attach the plates to unfinished castings providing the plates are shaped in a special manner and the castings are so made as to receive these special plates.

With the foregoing object outlined and with

other objects in view which will appear as the description proceeds, the invention consists in the novel features hereinafter described in detail, illustrated in the accompanying drawings and more particularly pointed out in the appended claims.

In the drawings:

Fig. 1 is a fragmentary top plan view of a side frame and bolster assembly, partly in horizontal section; such section being taken on the line 1—1 of Fig. 2. This assembly shows a known or old design.

Fig. 2 is a part vertical sectional view and part elevation of the same taken on the line 2—2 of Fig. 1.

Fig. 3 is a horizontal sectional view of my invention shown applied to the columns of a side frame and taken on the line 3—3 of Fig. 4.

Fig. 4 is a side elevation of the structure shown in Fig. 3.

Fig. 5 is a top plan view of an end portion of a bolster provided with my improved wear plates.

Fig. 6 is a side elevation of the structure shown in Fig. 5 with the bolster placed in vertical position to facilitate illustration.

Fig. 7 is a fragmentary plan view of a portion of a bolster and a horizontal sectional view of a portion of a side frame and illustrating a modification of the invention.

Referring first to Figs. 1 and 2, 8 designates a bolster having column guide surfaces provided with vertically arranged channel wear plates 9 having their vertical edges secured to the bolster by lines of welding 10, and their top and bottom edges welded in position by horizontal lines of welding 11. Here also columns 12 are provided with known channel wear plates 13 which are welded to the columns by vertical lines of welding 14 and by horizontal lines of welding 15.

The wear plates shown in Figs. 1 and 2 and 40 the manner of securing the same in position are open to the objections heretofore mentioned, and in accordance with the invention, the wear plates are made of L-shaped instead of channel shape, and as shown in Figs. 3 and 4 a pair of L-shaped 45 wear plates 16 are vertically positioned on columns 17 of a side frame and are secured in position by vertical lines of welding 18 and horizontal lines of welding 19. I prefer to provide the columns with rabbets 20 to receive the wear 50 plates.

As shown in Figs. 5 and 6, the guide surfaces of the bolster are also provided with rabbets 21 to receive L-shaped wear plates 22 which are secured in position by vertical lines of welding 23 55

and horizontal lines of welding 24 which function to make the plates substantially integral with the bolster.

Instead of spacing the adjacent edges of the 5 wear plates apart as shown in Figs. 3 to 6 inclusive, the inwardly extending wings 25 and 26 of the plates may be extended, as shown in Fig. 7, and the adjacent extremities of these wings may be welded together and to their respective cast- 10 ings by vertical lines of welding 27 and 28.

From the foregoing it will be understood that 15 in Figs. 3 to 7 inclusive, I have disclosed methods for applying renewable wear plates in a manner that avoids the difficulties mentioned above in connection with welding on channel pieces, and in each instance I show plates bended in the 20 shape of angles and that these plates are welded on to the casting along all edges of the plate in such manner that the welding does not project beyond the surfaces that are exposed to wear.

Obviously the purpose of the new construction is to obtain a snug fit between each wear plate and the casting to which it is attached without being confronted with the requirement of snugly 25 fitting channel pieces over a section such as that of a frame column or between fixed lugs such as those on a bolster. Furthermore it is obvious that angle pieces can be snugly attached regardless of the variation in the dimensions of the 30 frame column or the spacing of the bolster lugs. Channel pieces have to be made of fixed sizes for bolsters and columns, whereas angle plates of a given size may be used with bolsters and columns of substantially all sizes.

35 While I have disclosed what I now consider to be some preferred embodiments of the invention, I am aware that changes may be made in the details disclosed without departing from the spirit of the invention as expressed in the claims.

40 What I claim and desire to secure by Letters Patent is:

1. The combination with a railway truck side frame having a column, of a substantially L-shaped wear plate secured to the column, the column having a rabbet receiving said plate, the depth of said rabbet being equal to the thickness of the wear plate.

45 2. The combination with a railway truck side frame having a column provided with substantially L-shaped rabbets, of a substantially L-shaped wear plate arranged in each of said rabbets and secured to said column, the depth of each rabbet being substantially equal to the thickness of the wear plate which it receives, and the 50 column having a surface flush with the outer surface of portions of said wear plates.

55 3. The combination with a railway truck side frame having a column, of a substantially L-shaped wear plate secured to said column by

welded joints positioned at the edges of the wear plate, the column having a rabbet receiving said plate, the depth of said rabbet being equal to the thickness of the wear plate.

4. A combination with a railway truck bolster 5 having a column guide surface provided with a substantially L-shaped wear plate, secured to said bolster, the bolster having a rabbet receiving said plate, the depth of said rabbet being equal to the thickness of the wear plate. 10

5. A car truck bolster having a column guide surface provided with a pair of substantially L-shaped wear plates spaced from one another, the bolster having rabbets receiving said plates and said plates being secured to the bolster, the depth 15 of each of said rabbets being substantially equal to the thickness of the wear plate which it receives, and a portion of said surface being flush with portions of the outer surfaces of the wear plates. 20

6. In combination a railway truck side frame having vertical columns, a pair of wear plates protecting the bolster guide surfaces of each of said columns, each plate being substantially L-shape in horizontal section and the plates having 25 wings extending toward one another but spaced apart, each column having rabbets receiving said plates, the depth of each of said rabbets being substantially equal to the thickness of the wear plate, means securing the wear plates to the columns, the bolster guide surface having an unprotected portion positioned between said plates and arranged flush with the outer surfaces of portions of said plates. 30

7. In combination a railway truck side frame 35 having vertical columns, a pair of wear plates protecting the bolster guide surfaces of each of said columns, each plate being substantially L-shape in horizontal section and the plates having wings extending toward one another but 40 spaced apart, each column having rabbets receiving said plates, the depth of each of said rabbets being substantially equal to the thickness of the wear plate, means securing the wear plates to the columns, the bolster guide surface having an unprotected portion positioned between said plates and arranged flush with the outer surfaces of portions of said plates, in combination with a car truck bolster having column guide surfaces 45 provided with substantially L-shaped wear plates engageable with the wear plates of the vertical columns, each wear plate of the bolster being secured to the bolster, said bolster having rabbets to receive the last-mentioned wear plates, and 50 each rabbet of the bolster being substantially equal to the thickness of the wear plate which it receives. 55

HARRY A. MOELLER.
